(57) **CLAIM**

The ornamental design for a body support and alignment pillow, as shown and described.

DESCRIPTION

FIG. 1 is a front side perspective view of the first embodiment of the body alignment and support pillow;

FIG. 2 is a rear side perspective view thereof;

FIG. 3 is a first side view thereof;

FIG. 4 is a second side view thereof opposite the first side view;

FIG. 5 is a top plan view thereof;

FIG. 6 is a bottom plan view thereof;

FIG. 7 is a distal end view thereof;

FIG. 8 is a proximal end view thereof;

FIG. 9 is a front side perspective view of the second embodiment of the body alignment and support pillow;

FIG. 10 is a rear side perspective view thereof;

FIG. 11 is a first side view thereof;

FIG. 12 is a second side view thereof opposite the first side view;

FIG. 13 is a top plan view thereof;

FIG. 14 is a bottom plan view thereof;

FIG. 15 is a distal end view thereof;

FIG. 16 is a proximal end view thereof;

FIG. 17 is a front side perspective view of the third embodiment of the body alignment and support pillow;

FIG. 18 is a rear side perspective view thereof;

FIG. 19 is a first side view thereof;

FIG. 20 is a second side view thereof opposite the first side view;

FIG. 21 is a top plan view thereof;

FIG. 22 is a bottom plan view thereof;

FIG. 23 is a distal end view thereof; and,

FIG. 24 is a proximal end view thereof.
